US0D1041897S

(12) **United States Design Patent** (10) **Patent No.:** **US D1,041,897 S**
(45) **Date of Patent:** **** Sep. 17, 2024**

(54) **STORAGE BASKET**

(71) Applicant: **Lidi Xie**, Shenzhen (CN)

(72) Inventor: **Lidi Xie**, Shenzhen (CN)

(**) Term: **15 Years**

(21) Appl. No.: **29/854,268**

(22) Filed: **Sep. 23, 2022**

(51) LOC (14) Cl. **09-04**

(52) U.S. Cl.

USPC **D3/304**; D6/525

(58) **Field of Classification Search**

(57) **CLAIM**

The ornamental design for a storage basket, as shown and described.

DESCRIPTION

FIG. 1 is a first perspective view of a storage basket showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the storage basket that form no part of the claimed design.

1 Claim, 8 Drawing Sheets
